UNITED STATES PATENT OFFICE.

KARL J. SUNDSTROM, OF SIBLEY, MICHIGAN.

MIXING AND MEASURING MACHINE.

No. 861,778.

Specification of Letters Patent.

Patented July 30, 1907.

Application filed November 12, 1906. Serial No. 342,945.

To all whom it may concern:

Be it known that I, KARL J. SUNDSTROM, who am a citizen of the United States, residing at Sibley, county of Wayne, State of Michigan, have invented a certain 5 new and useful Improvement in Mixing and Measuring Machines; and I declare the following to be a full, clear, and exact description of the same, such as will enable others skilled in the art to which it pertains to make and use the same, reference being had to the accompanying 10 drawings, which form a part of this specification.

This invention relates to mixing and measuring machines; it has for its object improved means for proportioning and feeding into a receptacle or a mixing machine two or more materials.

15 The machine which embodies the invention, comprises two or more stationary receptacles located one above the other, or located side by side as may be most convenient. Within each of the receptacles is located a central cylinder, which may be either suspended 20 from the top, or supported on legs fastened to the bottom of the main receptacle, or the included cylinder may be movable upon and with a central shaft. Each of the main or outer receptacles is provided with a circular opening at the bottom below the inner cylinder.

25 The bottom through which this opening is cut, is spaced from the included cylinder and the included cylinder is larger in diameter than the circular opening through the underlying bottom of the receptacle, the difference being so great that the material used will rest 30 on the bottom of the main receptacle without falling through the opening; that surface of the material lying between the bottom of the included cylinder and the edge of the opening being at what may be termed "natural slope".

35 In the space between the bottom of the included cylinder and the bottom of the receptacle is located a sweep arm adjustably secured to a central shaft and arranged to sweep off from the edge surrounding the opening a portion of the contained material; the material swept off falls through the opening into the mouth of an included cylinder which lies in the receptacle below, or if the sweep be used in connection with the lowest cylinders of a series, into the final receptacle for the mingled material.

40 45 This apparatus is especially adapted for measuring and mixing wet, cohesive, sticky material such as slaked and partially cohering lime and wet sand, but it may also be used for dry materials, and for any material which is not so wet that it will flow, and thus prevent no "natural slope".

In the accompanying drawings:—Figure 1, is a vertical section showing a pair of main cylinders. Fig. 2, is a vertical section showing a pair of main cylinders with provision for introducing material at the side of the lower section. Fig. 3, shows a battery of three cylinders, delivering graduated amounts of material into the

shell of a conveyer. Fig. 4, is a plan indicating the location and action of the sweep. Fig. 5, is a plan of the lower member of the pair of mixers, shown in Fig. 2. Fig. 6, is an elevation of a sweep. Fig. 7, is a plan indicating two positions of a sweep, showing arrangement of adjustment. Fig. 8, is an elevation partly in section, showing the connection between a sweep and the shaft to which it is secured.

In the device shown in Fig. 1, there are two receptacles 1 and 2, mounted in vertical arrangement and supported by a suitable outer frame-work 3. Within the receptacle 1 is a cylinder 4 supported above the floor 5, of the main receptacle by legs 6. A central shaft 7 supported by inverted step bearings 71 rises 60 through both the receptacles 1 and 2, and is actuated from any convenient source of power, as by the screw 8 and worm wheel 9. Within the lower receptacle 2 is a cylinder 10, similar to the cylinder 4; this is supported on legs 11 resting on the bottom 12 of the receptacle 2. The mouth of the cylinder 4 is located above a circular opening 13 through the bottom 5 of the main receptacle 1, with the edge of the cylinder 4 so far back from the edge of the opening 13 that the material lying between the edge of the opening 13 and the edge 15 of the cylinder will assume its "natural slope" or less than its "natural slope" and will not travel by gravity from the containing part of the chamber across the zone 21 of the floor 5 and drop through the opening 13. The lower edge 17 of the cylinder 10 bears the same relation to the opening 18 through the bottom 12 of the lower receptacle. A sweep 19 is bolted to the shaft 7 and travels in a circular path, sweeping material off from the zone 21, through the opening 13, whence it drops into the 70 cylinder 10 and immediately drops into contact with the material that is sweeping off from the floor 12 through the opening 18. The sweep 9 is curved from the stem part 91 (see Fig. 7) by which it is secured to the shaft and the sweep part 92 passes across the 75 zone 21 at an angle to a radial line drawn through said zone; material lying on the zone is forced inward toward the center and through the opening 13. The 80

Agitators 22 and 23 may be secured to the shaft in either one of the forms shown, and with either one of the forms of receptacles shown. Agitators are used to advantage with some material, and are not of particular use with other materials.

The form shown in Fig. 2, shows funnel extensions 25 through which material may be introduced into 105 the lower main receptacle 32, and in this form the inner cylinders 33 and 34 are shown as secured to the shaft 37, and as themselves supporting the agitators 38 and 39, but the action is similar in all respects to the action of the device shown in Fig. 1.

In Fig. 3, the several receptacles are shown as erected 110 side by side, and as arranged to deliver graduated or

measured quantities of material into the chamber 41 of a screw conveyer 42. Feed spouts 43 deliver material into the outer receptacle of each of the measuring devices, and the inner cylinder 45 is shown in this case as fixed to the shaft 46, and as carrying the agitators 44. With this instrument the mixing might not be so intimate as with either of the forms shown in Figs. 1 and 2, but the proportioning of the parts of the mixture has the same certainty of quantity as 10 with either of the other forms of the device shown.

The form shown in Fig. 2, in which the inner cylinder rotates is especially applicable for use in connection with material that is particularly wet and sticky, such as partially wet lime, or wet sugar when the 15 device is used for mingling sugar and other substances.

What I claim is:—

1. A graduating device for mixers, having in combination a hopper provided with a central circular opening through the bottom thereof, a cylindrical tubular member located within said hopper and with its lower edge supported above the bottom of said hopper and retracted from the edge of said central opening, whereby there is formed between the said tube and the hopper bottom a support for material such that the material assumes a natural slope between the lower edge of the cylinder and the edge of the opening, a shaft extending through said central opening and through said central cylinder, a sweep secured to said shaft and adapted to sweep the hopper bottom underneath the edge of said cylinder, and means for rotating said shaft, substantially as described.
2. A graduating device for mixers, having in combination a hopper provided with a central circular opening through the bottom thereof, a cylindrical tubular member located within said hopper and with its lower edge supported above the bottom of said hopper and retracted from the edge of said central opening whereby there is formed between the said tube and the hopper bottom a support for material such that the material assumes a natural slope between the lower edge of the cylinder and the edge of the

opening, a shaft extending through said central opening 40 and through said central cylinder, a sweep secured to said shaft and adapted to sweep the hopper bottom underneath the edge of said cylinder, means for adjusting the sweep, and means for rotating the shaft, substantially as described.

3. In a device for measuring and mixing substances, the combination of a plurality of stationary hoppers located in vertical arrangement, each having a circular opening through its bottom, a cylinder in each hopper having its lower edge spaced from the bottom of said hopper and withdrawn from the edge of the opening through the bottom of said hopper, a shaft passing vertically through said hoppers and provided with sweep members, one for each hopper, each of said sweeps being adapted to force material toward and into said central opening, substantially as described.

4. In a measuring and mixing apparatus, in combination with a plurality of stationary hoppers arranged one over another, each provided with a circular opening through the bottom thereof, a cylinder located within each hopper having its bottom edge spaced from the bottom of said hopper and withdrawn from the edge of the opening through the bottom of said hopper, whereby provision is made for material to assume its natural slope, a sweep for each hopper extending from within the opening therethrough across a portion of the bottom thereof and under the edge of said included cylinder, substantially as described.

5. In a measuring and mixing device, in combination with a stationary receptacle provided with a circular opening through the bottom thereof, a rotary sweep adapted to force into and through said opening the desired proportion of the contents of said receptacle, a cylinder located in said receptacle above said opening with its bottom spaced from the bottom through which said opening is made, and with its lower periphery of larger diameter than the periphery of said opening, substantially as described.

In testimony whereof, I sign this specification in the presence of two witnesses.

KARL J. SUNDSTROM.
